UNITED STATES PATENT OFFICE.

EMIL B. MEYROWITZ, OF NEW YORK, N. Y., ASSIGNOR TO THE MEYROWITZ MANUFACTURING COMPANY, A CORPORATION OF NEW JERSEY.

OPHTHALMOMETER.

No. 275,278.

Specification of Letters Patent.

Patented Dec. 31, 1907.

Application filed May 29, 1906. Serial No. 319,271.

To all whom it may concern:

Be it known that I, EMIL B. MEYROWITZ, a citizen of the United States, residing at the city of New York, in the county of New York 5 and State of New York, have invented certain new and useful Improvements in Ophthalmometers, of which the following is a full, clear, and exact description.

My invention relates to a form of optical 10 instrument ordinarily used for measuring the curvature of the eye, and known as an ophthalmometer, although the special features which pertain to the invention are applicable to perimeters and a wide variety of other 15 instruments for precise measuring.

The principal object of the invention is to provide an apparatus of this class in which all the necessary adjustments and manipulations can be made from controlling mechanism 20 within convenient reach of the operator's hand, and in which the location of the various adjusting means is permanent and unvaried under all circumstances and conditions.

A further object of the invention is to 25 provide an indicating means in connection with apparatus of the above named character, which is adapted to register the final results of the measuring process directly on a convenient dial and without any special care or 30 difficulties on the part of the operator.

With these and other objects in view my 35 invention consists in the construction, combination, in the location and in the arrangement of parts, as hereinafter set forth and shown, and finally particularly pointed out in the appended claims.

In the drawings: Figure 1 is a side elevation 40 looking left in Fig. 1, the usual headrest for the patient being removed; Fig. 2 is a view on the line III—III of Fig. 2; Fig. 3 is a section on the line IV—IV of Fig. 2; Fig. 5 is a view of the dial which indicates the angular position 45 of the telescope; Fig. 6 is a view of the dial which registers the separation of the mires.

In an ophthalmometer it is usual to have 50 a telescope supported in a frame so as to be capable of swiveling on its axis, and certain prisms are arranged within the telescope so as to produce two images of an object, instead of the usual single image of the ordinary form. The purpose of this instrument is to measure the curvature of the eye, the 55 process being to direct the telescope toward

the eye and focus it on a luminous object or objects reflected from the surface of the eye cornea, in other words, to observe the angles at which luminous objects are reflected from the surface of the eye into the barrel of the 60 telescope. The luminous objects used are known as the mires, and are generally arranged on an arcuate frame forming a rigid part of the telescope, the mires being separable to different positions on said arcuate 65 frame. When the instrument is adjusted the luminous mires may be seen reflected from the surface of the eye through the barrel of the telescope, and the angles of reflection will depend on the eye's curvature. When 70 the telescope barrel is turned into one position, the angles may be of one value, and when it is turned into another position the angles may be of another value. The purpose of my invention is to facilitate making 75 the necessary adjustments and facilitating the measurement of these angles.

Referring now to the drawings in which like parts are designated by the same reference sign, 1 indicates a base-board or table 80 having standards 2 and 3 thereon. The standard 2 is the usual headrest, which need not be described, and the standard 3 carries a journal 4, in which the telescope barrel 5 is rotatably supported. 6 indicates the arcuate frame or support for the mires, shown at 7 and 7', and it will be understood that this arcuate frame 6 is rigidly attached to, and moves with the barrel 5 of the telescope, under all conditions. These features form the ordinary and well known construction of ophthalmometer, and constitute no part of my 90 invention.

Referring now particularly to Figs. 3 and 4 of the drawing it will be seen that the barrel 5 of the telescope has a dial 8, and a ring 9, which are both rigidly fixed thereto in addition to the arcuate frame 6 for the mires. The journal bearing 4 carries an annular housing 10 around the dial 8, and which has 100 an index 11, for registering the movement of the dial. The ring 9 of the telescope carries a pivoted pointer 12, which has a portion 12', constituting a detent, as will hereinafter more fully appear.

In addition to the above parts which are rigidly fixed to the telescope barrel, there is an additional part which is loosely sleeved upon it. I shall term this sleeve the mire adjustment, and it is indicated at 13 in the 110

drawing, and in the practical construction comprises a tubular portion 14, with an annular flange 15 upon the front side of which is inscribed a dial 16. This flange or dial is 5 conveniently protected by a housing 17, which is attached to, and forms part of, the main frame or standard 3.

18 indicates a gear which is cut on or attached to the mire adjustment 13, and 19 indicates a bevel gear in mesh with the gear 18, and connected to a small pinion 20, by a shaft 21. The shaft 21 is journaled in the frame 6 for the mires, so that the gears 19 and 20 always have a fixed axial relation to 15 the mire frame and to the telescope. Each of the mires has a curved rack 22, both in mesh with the pinion 20, so that when the pinion is turned, the mires are separated from one another or brought nearer together. 20 This result is secured whenever the gear 18 is turned relatively to the telescope barrel, but there is no adjustment of the mires in case the gear 18 rotates with the telescope barrel.

25 For the purpose of turning the mire adjustments relatively to the telescope barrel I have provided a short shaft 23, journaled in the standard 3, and having a pinion 24. 25 indicates gear teeth cut in the dial plate 30, 15, so as to be capable of meshing with the pinion 24. Referring to Fig. 3, it will be seen that the short shaft 23 is capable of longitudinal movement within its supporting standard, having a handle or button 26, by 35 which such movement is secured. 27 indicates a spring by which the button, and thereby its connected shaft, are normally pressed outward, so as to disengage the pinion 24 from the gear 25. Under these circumstances, the mire adjustment 13 turns 40 freely whenever the telescope barrel turns, and there being no relative movement of the gears 18 and 19, the position of the mires is not changed. In practice the friction of the 45 mires on their guides is considerable so that the mire adjustment 13 would be likely to turn with the telescope barrel, even if the pinion 24 were continuously in mesh, and in some cases I use this construction. I prefer, however, to preclude the possibility of 50 any movement of the mires on their frame when the telescope is moved by having the pinion 24 disengage itself when not in use by the spring connection above described.

55 In addition to the above features there is an auxiliary pointer 28, mounted on a ring 29, which is contained in an annular recess in the face of the dial plate 15, and which moves therewith unless otherwise restrained. This 60 ring and its connected pointer move with the dial, on account of the frictional engagement therewith at all points. The pointer 28 has, however, a slot 30, and this slot is in the path of the detent 12' previously mentioned, so 65 that when the telescope pointer 12 is thrown

inward, the detent 12' may be made to enter the slot 30 and hold the two pointers rigidly together, regardless of any independent movement of the dial plate 15.

The operation is as follows: I will imagine that the operator first wishes to measure the curvature of the eye in a horizontal plane. The telescope is, therefore, adjusted so that the zero mark of the dial 8 comes opposite the index 11. At this time the pointer 12 is 75 thrown up, so that the detent 12' is engaged with the slot 30, and the two pointers are, therefore, positioned together, pointing vertically at the center of the instrument. The operator now focuses the telescope on the 80 eye so as to see the images of the mires therein, and manipulates the button 26 by pressing it inward in the direction of the arrow in Fig. 4, so that the pinion 24 engages the gear wheel 25. The operator now turns the 85 button 26, transmitting motion to the mire adjustment 13, and the various gears 18, 19 and 20, the motion of which is effective to adjust the mires upon their frame. When the images within the telescope come to a certain 90 predetermined relation, which need not be described, the operator throws out the detent 12' from its engagement with the slot 30. The position of the pointers at this time upon the scale 16 indicates the separation of the 95 mires, and therefore the amount of curvature of the eye in a horizontal plane. I have shown the dial 16 with two different scales thereon adapted for the different purposes of optical measurement. I will now 100 assume that the operator wishes to measure the curvature of the eye in a vertical plane. He first turns the telescope barrel for example by taking hold of the arcuate frame 6 so that the 90° division mark comes 105 opposite the pointer 11. In this movement the mire adjustment 13 continues in unvarying relation with the telescope barrel. This is on account of its friction therewith, and on account of the friction of the mires, as above 110 stated. On account of the fact that the pinion 24 is disengaged from the gear 25, any possibility of error from its retardation of this part is precluded. The operator now observes the images of the mires in the new 115 relation, and manipulates the button 26 to move the mire adjustment 13 until proper conditions are secured as in the above case. Inasmuch as the pointer 28 is now disengaged from the pointer 12, said pointer 28 moves 120 with the dial plate, or, in other words, continues to point to the original register corresponding to the measurement for the horizontal curvature of the eye. The new adjustments are, of course, indicated by the 125 pointer 12, as before. Accordingly when the operator has finished, he has recorded upon the dial two measurements corresponding to the horizontal and to the vertical curvatures of the eye, and he also has the differ- 130

ence in the reading corresponding to the separation of the two pointers.

The feature which I wish to emphasize is the fact that under all circumstances and 5 conditions, the mire adjustment button 26 is in exactly the same unvarying relation to the frame and to the standard of the instrument. The operator is, therefore, always able to place his hand on the button without 10 looking for it, which is not only convenient in that it enables him to proceed without interrupting his observations, but is also, in some cases, really very important, because the observations are taken in a darkened 15 room, and if the position of the adjustment button is continually changed, the operator cannot find it, not being able to see it, and not knowing where to feel for it with his hand.

While I have shown the adjustment button 20 26 I do not regard this as absolutely essential, because the mire adjustment 13 has a fixed and unvarying relation to the standard and frame in the same way as the button 26. In some cases I may, therefore, make the mire 25 adjustment by manipulating the dial plate 15 directly with the fingers, instead of through the pinion 24. For this purpose the housing 17 would, of course, have to be removed.

30 What I claim is:—

1. In an ophthalmometer having a telescope and mires adjustable, with relation thereto, axial means for adjusting the separation of the mires, said means having an 35 unvarying axial position during the turning of the telescope.

2. In an instrument of the class described having a telescope and mires adjustable with relation thereto, a mire adjustment co-axial 40 with the telescope, whereby its axial position is unchanged when the telescope is turned.

3. In an instrument of the class described having a telescope and mires adjustable with relation thereto, a mire adjustment co-axial 45 with the axis of the telescope, said adjustment having a dial also concentric with the telescope.

4. In an instrument of the class described having a telescope with a dial, and mires adjustable with relation to the telescope, a mire adjustment co-axial with the telescope and having a dial, said dial being co-axial with 50 the dial of the telescope.

5. In an instrument of the class described

a telescope having a sleeve adjustable thereon, said sleeve having a portion with gear teeth, a pinion movable into and out of mesh with said gear teeth, and means whereby said pinion may be moved into intermeshing relation when desired. 55

6. In an instrument of the class described having a telescope and mires, a telescope having a sleeve adjustable thereon, said sleeve having a portion with gear teeth, a pinion movable into and out of mesh with 60 said gear teeth, means whereby said pinion may be moved into intermeshing relation when desired, and gear connections from said sleeve to said mires whereby they are adjusted when the sleeve is turned. 70

7. In an instrument of the class described, a telescope having parts connected thereto for making measurements and observations, a dial connected to the telescope for indicating its angular position, a sleeve on the telescope also having a dial, and connections from said sleeve to said parts for adjusting them with relation to the telescope. 75

8. In an instrument of the class described, a telescope having mires adjustable with relation thereto, a mire adjustment co-axial with the telescope having gear teeth, a pinion spring pressed out of engagement with said gear teeth, and means for moving said pinion into intermeshing relation and turning it 80 when desired. 85

9. In an instrument of the class described, a telescope having parts adjustable with relation thereto, a sleeve on the telescope for adjusting said parts, a dial on said sleeve, a 90 pointer on the telescope indicating on said dial, and an additional pointer normally movable with the dial, said last named pointer having means whereby it may be locked in immovable relation with respect to 95 the telescope.

10. In an instrument of the class described, a telescope having a sleeve adjustable thereon, a shaft connected to rotate said sleeve, and means whereby said shaft 100 may be disengaged from the connection with the sleeves.

In witness whereof, I subscribe my signature, in the presence of two witnesses.

EMIL B. MEYROWITZ.
